UNITED STATES PATENT OFFICE.

JOSEF PĚTICKÝ, OF PRAGUE, AUSTRIA-HUNGARY.

APPARATUS FOR AUTOMATICALLY CONNECTING UP THE SUBSCRIBERS OF TELEPHONE-EXCHANGES.

1,047,833.

Specification of Letters Patent.

Patented Dec. 17, 1912.

Application filed March 7, 1905. Serial No. 248,634.

To all whom it may concern:

Be it known that I, JOSEF PĚTICKÝ, a subject of the Emperor of Austria-Hungary, and resident of Prague, Austria-Hungary, 5 have invented certain new and useful Apparatus for Automatically Connecting up the Subscribers of Telephone-Exchanges, of which the following is a specification.

This invention has reference to means for 10 automatically connecting up the subscribers in telephone exchanges.

Said means consist of apparatus for each subscriber, or each call office, and connecting-up apparatus in the exchange. For each 15 subscriber there are two call apparatuses, one fitted alongside his telephone and one fitted in the exchange, so there are altogether as many sets of call apparatus as there are subscribers or call stations, while 20 the number of connecting-up apparatuses in the exchange is determined by the largest number of conversations estimated to be likely to be carried on simultaneously.

The subscribers' call apparatus serves for 25 determining and making particular contacts for the electric current, through the making and breaking of which in the exchange certain movements of the relative apparatus in the exchange—and of the connecting-up apparatus—are brought about. With the help of any one of the call apparatus in the exchange, connection can be made with any 30 one of the connecting-up apparatus, and thus any two subscribers can be connected up. As, however, different connections have 35 continually to be made, and the connecting-up apparatuses are engaged therefore intermittently, the call apparatus in the exchange is designed to automatically dis-

40 cover a disengaged connecting-up apparatus, and that in such a manner that when, for example, ten conversations are being carried on at one time ten of the connecting-up apparatuses will be engaged in order one 45 after the other. When a new connection is to be made in these circumstances, the exchange call apparatus makes connection with the eleventh connecting-up apparatus; but if in the meantime, for example, the 50 sixth connecting-up apparatus is set free, then the next or twelfth connection would be made through this disengaged sixth apparatus. The connecting-up apparatus discovers 55 automatically the required subscriber's line by his number and makes the desired con-

nexion. Each one of the three apparatuses is designed to automatically return to its normal or disengaged position on the conclusion of a conversation, so that new connections can be made.

The construction of the apparatus employed may vary. I have illustrated in detail and diagrammatically one form in the accompanying drawings, in which—

Figures 1 to 6 show one form of subscribers' call apparatus: Fig. 1 being a back view of the contact plate, Fig. 2 a front view, Fig. 3 a front view, with the front of the case in which the apparatus is housed removed, Fig. 4 a vertical section, and Figs. 5, 6 and 7 show the means for putting this apparatus into and out of operation, Fig. 5 being a side view, Fig. 6 a front view, and Fig. 7 being a diagrammatic view partially in section of a portion of the mechanism shown in Figs. 5 and 6. Fig. 8 is a side view of a portion of the selecting mechanism; Fig. 9 is a top plan view of the mechanism shown in Fig. 8. Figs. 10 and 11 are end views in detail of portions of the mechanism shown in Figs. 8 and 9; Figs. 12, 13, 14, 15, 16, 17, 18, 19, 20, 21, 22 and 24, are views in detail of the rotating selecting wheels, contacts, and connecting mechanisms, shown in various positions in diagram, and Figs. 23, 25 and 26 show the entire station installation as the same appears when viewed from various points, while Fig. 27 is a fragmentary view showing elements of the installation in a different operative position. Figs. 28 and 29 show diagrammatically the various circuit wires and connections.

This subscribers' call apparatus consists of operating mechanism 1, on the spindle 2 of which an arm 3 is secured which carries on its end three spring contacts 4, 5 and 6 which slide over a fixed plate 7, made of insulating material and this arm 3 is actuated at the proper moment by a spring or other suitable motor of any desired form, which it has not been deemed necessary to show herein. In this plate, a number of contacts are let in, which contacts are arranged in particular groups.

Commencing from the normal or disengaged position of the arm 3, shown in Fig. 1, and following the direction of movement of the latter, the first contact group, of, for example fifteen to twenty contacts, is indi-

cated by the numeral 8, which group serves to actuate the relative call apparatus in the exchange so as to discover a disengaged connecting-up apparatus. Then follow four contact groups, 9, 10, 11, 12 each comprising eleven contacts, of which always the first 9^a, 10^a, 11^a, 12^a, serves to actuate the contact device A, hereinafter described, of the connecting-up apparatus (Fig. 23), while the other ten contacts 9, 10, 11, 12 serve to actuate the contact devices B, C, D and E of said connecting-up apparatus, that is to say, for making the connections with the number called. Then there are two contacts 13 by means of which the contact device A is displaced two teeth. In the other half-circle of this plate, a contact 14 is disposed which serves to make the connection for speaking; then there follow four contact groups 15, 16, 17, 18, each comprising twelve contacts, of which those marked 15^a, 16^a, 17^a, 18^a, serve to bring about the movement of the contact device A, while the others 15, 16, 17, 18, serve to actuate the contact devices B, C, D, E. Then follow two contacts 19 for displacing the contact device A; behind these two contacts 19 a special contact may be provided whereby direct connection with the exchange may be established. The last contact in the circle, 20, serves to permanently connect the subscriber with the exchange for the purpose of receiving calls from other subscribers.

The contacts 4 and 5, which are connected together, slide over the contacts 8, 9^a, 9, 10^a, 10, 11, 12^a, 12, 13, 15^a, 15, 16^a, 16, 17^a, 17, 18^a, 18, and 19, and the contact 6 slides over the contacts 14 and 20, and the electric current is conducted to these contacts by known means from rings and lamellæ fixed on the spindle 2. The contacts referred to, 9, 10, 11, 12, through which the contact devices B, C, D and E are actuated in discovering the number of the subscriber called, may be covered as required by means of insulated shields 21, 22, 23, 24, whereby a displacement of the contact devices B, C, D, E, by as many teeth as there are free, *i. e.* uncovered, contacts remaining may be accomplished. In a similar manner, the contacts 15, 16, 17, 18, through which the contact devices B, C, D, E, are operated to bring them back to their normal or disengaged positions, may be covered by insulated shields 25, 26, 27, 28, which latter are so coupled in pairs by means of the rotatable arms 29 mounted on the axis of the apparatus that by uncovering a predetermined number of contacts in the groups 9, 10, 11, 12, a like number of contacts in the groups 15, 16, 17, 18 will be covered, the result of which is that the contact devices B, C, D, E, which have been displaced or moved to correspond with a particular number, will be turned relatively to the number 65 of teeth remaining between that position

and the normal or disengaged position, *i. e.* to the end.

From the arms 29, hand levers 30 provided with springs project through the front of the subscribers' apparatus and on this front cover a numbered index (Fig. 2) with groups of figures from 0 to 9 is applied, of which the first on the left is for thousands, the second for hundreds, the third for tens, and the fourth for units, so that any number from 0 to 9999 can be made up.

If the apparatus is to be designed for a larger number of subscribers than 10,000, an extra contact is provided in the group 9, whereby the total will be increased by 1000; 80 in the connecting-up apparatus corresponding alterations will be made.

By placing the hand levers 30 on various figures of the index, the shields 21, 22, 23, 24, take up such a position that they always uncover one more contact than the hand lever indicates on the index, because there is also a contact for the 0. If for example the subscriber's number 2458 is to be called, the hand levers will be moved to the corresponding figures on the index, whereby three contacts in group 9, five contacts in group 10, six contacts in group 11, and nine contacts in group 12 will be uncovered, the result of which will be that the contact device B will be moved three teeth, the contact device C five teeth, the contact device D six teeth and the contact device E nine teeth. Simultaneously, a like number of contacts in the groups 15, 16, 17, 18 will be covered, so that 100 in the order named 8, 6, 5, and 2 free contacts remain, by means of which the contact devices B, C, D, and E, will be moved back into their normal or zero position.

In the drawings 0 has a particular contact position, so that when a number having a 0 in it is called up the relative apparatus moves forward one tooth on setting the hand lever 30 on the relative 0. This arrangement may however be dispensed with and instead of it the contact devices may normally stand on 0, so that when a number with a 0 in it is called, no movement of the contact device is necessary.

The arm 3 is held in the zero position by means of the adjustable stop 31; if this stop be moved by pressing in its spindle 32 said arm 3 will be set free and will rotate in the direction of the arrow 33, through an angle of 180°, whereby the connection with the subscriber called up will be made and the arm will be brought to a stand by means of a special stop device. This stop device consists of the lever 34 (Figs. 5, 6 and 7) which is rotatable on the bolt 35 and carries a double stop which comprises an upper tooth 36 and a lower tooth 37 the latter of which is disposed sideways. When the arm 3 reaches this tooth 36 (position 3^a) it is held thereby and the apparatus thereby stopped.

If, however, the lever 34 be moved in the direction of the arrow 39, the arm 3 moves a little farther, and will then be stopped by the tooth 37. If the lever 34 be moved in the direction of the arrow 39, the arm 3 will be set free and will continue to move in that direction. These two movements of the lever 34 are attained by the aid of the lever 41, which is provided with an arm 40 and is mounted loosely on the same spindle, which lever 41 carries the three usual contacts and on which the receiver is hung. If the receiver is removed for the purpose of speaking, the lever 34 is moved (Figs. 5 and 7) so that the arm 3 can move a little farther, while, when the conversation is finished, the receiver is again hung up, the said lever 34, turns in the reverse direction, so that the arm 3 is again set free and in its further progress makes the necessary contacts for bringing back the whole of the apparatus to its zero position, until, finally, it is brought to a standstill by the stop 31.

The exchange apparatus, which is shown in Fig. 8 in front view and in Fig. 9 in plan view, comprises a contact device and a lever mechanism. The contact device comprises the ratchet wheel 42, in which a pawl 43 engages, which latter is moved by an electro-magnet 44 and thus turns the ratchet wheel. On the spindle of the wheel 42, a disk 45 provided with contacts is fixed. On this disk there is a row of five contacts 46 which slide over a fixed contact disk 47. In this there are fifteen to twenty contact rows 48, 49, 50, 51, etc., their number being according to the number of the connecting-up apparatuses, that is there are as many contact rows as there are connecting-up apparatuses in the exchange. The number of these contact rows corresponds to the number of contacts 8 in the subscriber's call apparatus.

The electric current is conducted to the movable contacts 46 by means of lamellae and rings as in the case of the subscribers' call-apparatus. On the lower end of the double armed lever which rotates the ratchet wheel 42 there is a contact 52 which makes contact with the fixed contact when this lever is attracted by the electro-magnet.

The lever mechanism of the exchange apparatus, of which Figs. 8, 9 and 10 show a front, plan, and side view respectively, and Fig. 11 shows a front view at the moment of its operation, comprises a lever 54, which is actuated by an electro-magnet 53 and on the upper end of which there are five contacts 55, 56, 57, 58 and 59, while its lower end is provided with a contact 60. Opposite the two highest contacts 55, 56, there is a second movable lever 61 with two contacts 62, 63, opposite the three middle contacts 57, 58 and 59, is a fixed bracket 64 with three contacts 65, 66, 67, and opposite the contact 60 there is a

fixed contact 68. When the lever 54 is at rest (Fig. 8) a connection is made between the contacts 56, 63, and the lower contacts 60, 68, while the contacts 55, 57, 58 and 59 are out of contact with the contacts 62, 65, 66, 67, and thus until after setting in operation of the whole apparatus, a disengaged connecting-up apparatus has been connected. When the lever 54 is attracted by the electro-magnet 53, the four remaining upper contacts 55, 57, 58 and 59, make contact with the contacts 62, 65, 66, 67, while the contacts 56 and 60 leave the contacts 63 and 68. At this moment both levers 54 and 61 are retained by means of a lever 69 which is provided with two stops which lever 69 lies loose on the levers 54 and 61 when at rest, whereby any backward movement whatever of the lever 61 is prevented, while a slight movement of the lever 54 is permitted after shutting off the current in the electro-magnet 53 so that then both levers 54 and 61 remain in the position shown in Fig. 11. In this position the upper contacts 55, 62, and 56, 63, and the lower contacts 60 and 68 are out of contact while the middle contacts 57, 58 and 59 are in contact with 65, 66, and 67. When thereafter the electro-magnet 70 attracts the lever 69, both levers 54 and 61 are returned to their original or zero position.

The exchange apparatus described serves as already stated, for discovering disengaged connecting-up apparatus, which is accomplished with the aid of lever mechanism 71, 72, 73, belonging to each connecting-up apparatus and similar to the already described lever mechanism 54, 61, 64, and 69. This lever mechanism (Figs. 12 and 13) comprises a lever 71 which is actuated by an electro-magnet 74, and is provided with two contacts 75 and 76 at its upper and one contact 77 at its lower end. Opposite the middle contact 76 there is a second movable lever 72, which is provided with a counter-contact 78; opposite the upper contact 75 on the lever 73 is a counter-contact 79 and opposite the contact 77 a fixed counter-contact 80. The contact 75 is coupled with the contact 76. When the lever 71 is attracted by the electro-magnet 74, the lever 72 moves, the under contact is broken, the lever 73 springs in and holds the lever 72 by means of its stops, while the lever 71 moves back a little after the current is shut off in the electro-magnet 74 until contact is again made between the contacts 75 and 79. When the lever 73 is drawn to the electro-magnet 81 both levers 71 and 72 move back and contact is again made between the contacts 77 and 80.

The contact 79 on the lever 73 of the first connecting-up apparatus is, as shown diagrammatically in Fig. 29, connected with the contact 75 of the second apparatus, the contact 79 of the second apparatus with the

contact 75 of the third, and so on, the contact 79 of one apparatus being always connected with the contact 75 of the next in order.

5 The connecting-up apparatus, which is shown in Figs. 14-27, consists of five contact devices A. B. C. D. and E. and a predetermined number of contact rods 82. The contact device A. (shown in detail in Figs. 20 to 22) serves for bringing about the movements of the contact devices B. C. D. and E. and of the contact rods 82, and that in such a manner that it connects up the current to the relative electro-magnets. This contact device A. comprises a fixed disk 83, shown in Fig. 21 in a view from below and in Fig. 23 in plan view, and a movable disk or sector 84, shown in plan in Fig. 22, which is disposed below said fixed disk and is provided with ten contacts 85, of which always two neighboring contacts are coupled in pairs and alternately make the connection between the contacts in the upper disk. These consist of the contact groups 86, 87, 88 and 89 for the actuation of the electro-magnets 90, 91, 92 and 93 for rotating the contact devices B. C. D. and E. in selecting the number of the subscriber called up, of contact groups 94, 95, 96 and 97 for the actuation of the same electro-magnets for moving the contact devices into their zero position, further, of two contacts 98 and 99 belonging to the contacts 86-89 already referred to, of the contact 100 for making the connection for speaking, of the contact 101 for connecting up the current to the electro-magnet 81 or 70 for the purpose of returning the lever mechanism of the exchange apparatus and of the connecting-up apparatus to its zero position, of the contacts 102 and 103 for moving the rod 82 for making the connection for speaking and for returning the same when the conversation is finished, and finally of two contacts 106 and 45 107 which come into operation when a subscriber is already engaged when someone else wishes to speak with him, these last mentioned contacts serving also to prevent any other subscriber overhearing the conversation being carried on. For the purpose of making direct connection with the exchange, an extra contact may be provided on the disk 83. The various contacts referred to in the disk 83 are arranged in several quadrants or sectors and the like operating contacts in the several quadrants are connected up with each other. To each of the contact groups described belong contact rings 108, 109, 110, 111 and 112. The disk 55 84 is moved by the electro-magnet 113 by means of a ratchet wheel 114 and a lever, on which latter a contact 115 is fixed which on the actuation of the electro-magnet makes the connection between the contacts 116.

60 65 The other contact devices B. C. D. and E.

serve for selecting the number of the subscriber called up, the contact device B. serving for thousands (or higher), C. for hundreds, D for tens, and E for units. Each of these contact devices consists of a disk 117, 70 or 118, 119, 120 in which a certain number of contacts are let in, and of a movable disk or sector 121, or 122, 123, 124 mounted below said disk and provided with contact groups of four contacts each, of which each two neighboring contacts are connected up in pairs and make alternately the connection with the contacts in the fixed disk. Each movable disk is moved or rotated by means of a lever actuated by the electro-magnets— 80 the contact device B. from the electro-magnet 90, C from 91, D from 92 and E from 93.

The fixed disk 120 of the contact device E, which is shown in Fig. 15 in a view from below and in Fig. 23 in plan view, carries one 85 hundred contacts 125, which are arranged in groups of ten, and ten contacts 126, of which each one belongs to one of the groups 125 and is connected up with the former by means of movable contacts 127 (Fig. 25). 90 In addition, a like number of similarly arranged contacts 128 and 129 are carried by the disk 120, and contacts 130 by the movable disk. Similarly to E, the contact device C is provided with contacts 130, 131, 95 and 132 and contacts 133, 134 and 135. In addition, this device has two contacts 136 and 137 which are connected up with the zero contacts 130 and 133 of the first group. The contact device D carries two groups 138 100 of eleven contacts each and the contact ring 139, which are connected up by movable contacts of any suitable sort, (not shown), and a like number of similarly arranged contacts 141, 142 and 143. The contact device B is 105 furnished with contacts arranged in a similar manner to those on D and carries the contacts 144, 145 and 146, and the contacts 147, 148 and 149. The contacts 128 on the contact device E, and the contacts on C of 110 the first connecting-up apparatus are progressively connected up with the like contacts of the second, third, fourth, etc., connecting-up apparatus.

The contact rods (Figs. 23, 26 and 27) 115 serve for the actual connecting up of the subscribers for conversing. Each of these rods is slidably arranged in a fixed frame 150 and carries one hundred contacts 151 to which the wires of the individual subscribers are connected and which by means of the relative contacts make the connections with all the connecting-up apparatuses, so that, accordingly, the number of hundreds of subscribers to the exchange represents the 125 number of contact rods of the connecting-up apparatus. For example, for 3000 subscribers 30 rods are necessary. To each of these contact rods, belong electro-magnets 104 and 105. Under each contact rod there 130

are one hundred fixed contacts 152, which are connected up with each other in such a manner that, for example, the first fixed contact 152 of the first rod is connected up 5 with the hundred-and-first contact of the second rod, then with the two-hundred-and-first contact of the third rod, and so on, so that the hundredth fixed contacts 152 in each row across the whole series are connected up with each other (Fig. 23). When 10 a contact rod is in its zero position (Fig. 27) there is no contact between the contacts 151 and 152, but when the current is connected up to the electro-magnet 104, the rod is displaced 15 so that it makes simultaneously one hundred contacts between 151 and 152, in which position the rod is retained by means of the hook 153 until said hook is raised by means of the electro-magnet 105.

20 On each contact rod a connection-contact 154 is arranged opposite a counter-contact 155 fixed on the frame. The contacts 152 (Figs. 23 and 28) are connected up in order with the contacts 125 on the contact device 25 E, and the contacts 126, which belong to the whole group of ten last contacts, are connected up in order with the single contacts 138 of the contact device D. In like manner, the electro-magnets 104 connect with the 30 contacts 130 on the contact device C and the contacts 131, which belong to the whole contact group 130, make the connections—in order—with the single contact 144 on the contact device B. This connection is shown 35 in Fig. 23. The contact 138 corresponding to 0 on the contact device D is connected up with the contact 126 which pertains to the first of the contact groups 125, *i. e.* from 0 to 9 on the contact device E and controlled there- 40 by, the contact 138 in the second row corresponding to units on the contact device D is connected up with the contact 126 of the second contact group *i. e.* from 10 to 19, and so on. Accordingly the sixth in the row, the 45 corresponding contact 138 to the number 5, is connected up with that contact 126 which belongs to the sixth contact group, *i. e.* from 50 to 59. Thereby the contact 125 corresponding to the number 8 on the contact de- 50 vice E, is connected up after the disk 124 is rotated, which contact is in the sixth group, from 50 to 59. This corresponds to the fifty-eighth contact on the contact device E and on all the contact rods (Fig. 23).

55 A like arrangement is made in the case of the contact devices B and C. Take for example the third contact 144 on the contact device B which corresponds to the number two which is connected up with that contact 60 which belongs to the third contact group 130 *i. e.* from 20 to 29. By this the contact on the contact device C corresponding to the number 4 comes into operation on the rotation of the disk 122, which contact be- 65 longs to this third group and which corre-

sponds with the twenty-fourth contact on the contact device C, the electro-magnet 104, and the twenty fourth contact rod. When the circuit energizing the magnet 104 is closed the twenty-fourth contact rod on 70 which are the contacts 2400 to 2499 as shown in Fig. 26 is slid so as to enable its fifty-eighth contact to make the connection corresponding to the subscriber's number 2458.

The whole of the apparatuses described 75 are connected up with each other in the manner shown diagrammatically in Figs. 28 and 29 with the result that they operate as will now be described.

When a subscriber, for example wishes to 80 call up No. 2458 he places the pointer carried by the hand lever 30 on the relative numbers on his index. As has been already described there will remain in the contact group 9 three, in group 10 five, in group 11 85 six and in group 12 nine free contacts; simultaneously a like number of contacts in the groups 15, 16, 17 and 18, are covered up so that, in order, eight, six, five and two free contacts remain. Thereupon the 90 spindle 32 is pressed in, whereby the stop 31 is displaced; this sets the arm 3 free which consequently moves in the direction of the arrow 33. By this movement the contact 4 makes connection with the first contact of 95 the group 8 whereby a circuit is established from the battery 157, contact 56, contact 63, magnet 44, subscriber's call apparatus including contact 4, ground C', through the earth to ground G² and thence back to the 100 battery 157. This circuit is shown by the connecting wires being marked 156 and will be hereinafter referred to as the circuit 156, it being understood that certain parts of this circuit also form parts of other circuits so 105 that the word "circuit" as hereinafter used refers to the complete route traversed by a current in performing a specific operation. Thereby the armature of the electro-magnet 44 is attracted and the ratchet wheel 42 and 110 the disk wheel 45 are rotated one tooth so that the contacts 46 on the next following contact row on the disk 47, for example, make contact with the contacts 48. When these contacts are in connection with a disengaged connecting-up apparatus, the circuit through the connecting up apparatus, hereinafter referred to generally as the circuit 158 and indicated by that reference numeral on the drawing is closed. The circuit 156 115 120 will simultaneously be broken as described below. This automatic searching for and finding a disengaged connecting-up apparatus will be understood from the diagrammatic representation of the various connections shown in Fig. 29, and hereinafter explained. Presuming the first connecting-up apparatus to be disengaged the circuit 158 will be closed by the action of the current through circuit 156 and the bringing to- 125 130

gether of the contacts 52, the current in which circuit 158 originates in the battery 157 and circulates through said contacts 52, electro-magnet 53, contacts 46 and 48, electro-magnet 74, and contacts 78 76 and 75. The 5 electro-magnets 53 and 74 attract and draw back their armatures whereby contact is broken between the contacts 56 and 63, so that on further movement of the arm 3 over 10 the contacts 8 the circuit 156 will be broken, the wheel 45 thus remaining stationary and all further currents (from the contacts) act directly upon this disengaged connecting-up apparatus. If however the connecting-up 15 apparatus is not free, *i. e.* when the contact 76 of this apparatus is not in circuit, the circuit 158 will not be closed, the current in which circuit had actuated the armature of the electro-magnet 53 and prevented the new 20 circuit 156 being closed, but on the movement of the arm 3 over the second contact of group 8, the circuit 156 will again be closed and thereby the ratchet wheel 42 will be rotated a further tooth. Now the contacts 25 49 which correspond with the second connecting-up apparatus come into play. If this apparatus be free, the circuit 158 is closed (the path of the current being shown in dot and dash lines in Fig. 29), the current 30 in which circulates from the battery 157 through the contacts 52, electro-magnet 53, contacts 46 and 49 of the exchange apparatus, electro-magnet 74 and contacts 78 76 and 75 of this second connecting-up 35 apparatus and contacts 79 and 75 of the first connecting-up apparatus. Thereby the armature of the electro-magnet 53 of the exchange apparatus and that of the electro-magnet 74 of the second connecting-up 40 apparatus will be actuated, whereby connection between the contacts belonging thereto 56 and 63 will be broken so that the further passage of current in the circuit 156 and rotation of the wheel 45 will be stopped. In 45 this manner it can be seen that those of the subsequent connecting-up apparatuses are free or disengaged the lever mechanism of which is in its zero position or the contacts 76 and 78 of which are in touch.

50 When a disengaged connecting-up apparatus has thus been found and the armatures of the electro-magnets 53 and 74 have been actuated, the lever 54 takes up the position shown in Fig. 11 so that continuous 55 touch between the contacts 57, 58 and 59, and 65, 66 and 67 is maintained. When therefore the contact 4 in the subscribers' apparatus is brought over the contact 9^a, a circuit hereafter called 159 is closed, the 60 current in which circuit circulates from the battery 157 through the electro-magnet 113, in connection with the contact device A, contacts 49 and 46, contacts 58 and 66, contacts 9^a, contact 4 on the arm 3 ground G', 65 ground G², and back to the battery. There-

by the armature of the electro-magnet 113 will be actuated, the disk of the contact device A will be rotated one tooth, and the contacts 86 will make the connections for the actuation of the contact device B (161 Fig. 23). Thereupon the contact 4 comes in contact with the first, *i. e.* the 0 contact of group 9, whereby a circuit hereafter known as the circuit 173 is closed, the current in which circulates from the battery 70 157 over the contacts 108, 85, and 86, in the contact device A, the electro-magnet 90, the contacts 98, and 109 in the contact device A, the contacts 49 and 46 in the exchange apparatus, the contacts 57 and 65, the relative contact 9 on the subscribers' call apparatus, the contact 4 ground G', ground G², and back to the battery. By the action of the current the armature of the electro-magnet 90 will be actuated, whereby the contact 85 device B or its disk 121 will be rotated one tooth on to 0. Through the next contact in group 9, the disk will be rotated another tooth on to 1. Through the further contacts 90 the disk will be actuated each time by one tooth, this recurring as often as there are free contacts in this group 9, accordingly when the disk has been actuated three teeth it will indicate two thousand. Thereupon 95 the circuit 159 is closed by the instrumentality of the contacts 10^a, the current actuating anew the contact device A so that it is moved a second tooth (162 Fig. 23), whereby the connection of the contact device C with the electro-magnet 91 is made. When 100 thereupon the contact 5 reaches the first of the contacts 10 the circuit hereinafter called the circuit 174 and indicated by the numerals 174 is closed the current in which circulates as in circuit 173 with the difference however that it passes through the contact 87 and electro-magnet 91, whereby the contact device C is moved one tooth on to 0. Through the next contacts 10 the contact 105 device C is further rotated being moved as many teeth as there are uncovered contacts in the group 10, accordingly, as in the example already given, by five teeth, which represents four hundred. Then the contact 11^a comes into operation and through it the 110 circuit 159 is again closed so that the contact device A is rotated a third tooth (163 Fig. 23), whereby the connection for the actuation of the contact device D is made. When the contact 4 engages the first of the 115 contact group 11, the circuit hereinafter called the circuit 175 and indicated by the numerals 175 is closed, the current in which flows along the path taken by the current in the circuits 173 and 174, except that it passes 120 through the contact 88 and the electro-magnet 92; the contact device D is rotated by as many teeth as there are uncovered contacts remaining in the group 11, accordingly in 125 the present instance by six teeth. (Five 130

tens). Then the contact 12^a comes into play for the circuit 159, the contact device A is rotated a fourth tooth 164, the circuit hereinafter called the circuit 176, and indicated by numerals 176, the current of which flows along the path common to the circuits 173, 174, and 175, and through 89 and 93, is closed through the contacts 12 so that the contact device E is moved by as many teeth 5 as there are uncovered contacts remaining in the group 12, accordingly in this example, by nine teeth, which corresponds to eight units. Thereupon the contact 4 makes contact with the first of the contact group 13, 10 the circuit 159 is closed, the contact device A is rotated a fifth tooth, 165, and closes the circuit hereinafter called the circuit 177 and indicated by the numerals 177, the current in which circulates from the battery through 15 a pair of normally closed contacts 178, which are arranged to be opened by an electro-magnet 179 in a circuit hereinafter to be described, contact 147, contact 144, contact 131, contact 130, already found (or in the 20 case of a smaller number than one hundred, through the contacts 136) to the contact devices B and C, the electro-magnet 104 which corresponds with said contacts 130 (or 136), and the contact 102 and ring 111 in the contact 25 device A and thence back to the battery 157. The magnet 104 corresponding to the twenty-fourth contact rod is energized and the rod moved, the rod bearing the contacts 2400 to 2499, whereby communication with 30 the desired subscriber's number is obtained. Simultaneously the hook 153 falls into the tooth of the displaced contact rod so that the latter is retained thereby until the electro-magnet 105 raises the hook out of engagement. This takes place only on the 35 conclusion of the conversation as herein-after explained. After this the contact 4 engages the second contact 13, whereby the contact device A is rotated a sixth tooth, 166, and the connection for speaking with the subscriber called, is made. Thereupon 40 the arm 3 comes against the tooth 36 and is held. The subscriber calling up signals through the circuit 180 (or 181). The current in this circuit, commencing with earth, 45 flows through the telephone apparatus of the calling subscriber, the current entering by the switch S, and passing successively through the bell b, contact e, contact e', fork f, and out to contacts 6, and 14, on said subscriber's call apparatus, contacts 57 and 65 50 on the lever mechanism of the exchange apparatus, contacts 46 and 49, contacts 109, 85 and 100 in the contact device A, the contacts 138 and 125 corresponding to the particular number on the contact devices D and E and the connection in the contact rod 82. Here the current flows over into the apparatus 55 of the subscriber called (circuit 181, shown in Fig. 28 in dotted lines) through

the contacts 60 of the lever mechanism of the exchange apparatus, the contacts 20 and 6 of the subscriber's call apparatus (as the arm 3 there stands in its zero position), the telephone and to earth. On the caller receiving the reply signal from the subscriber called, both subscribers remove their receivers, whereby the arm 3 of the caller's call apparatus is set free and moves a little farther until it comes in contact with the tooth 37. Then conversation can take place. The circuit being that exterior to the subscriber's telephones over which signaling took place, the instruments being brought into circuit by the removal of the receiver r, 70 from its hook whereby the circuit is closed through the contacts c² and c³. The current from the subscriber's call apparatus thus passes from contact 4, through receiver r, 75 secondary of the transformer T, switch S, 80 to ground G'. At the same time a local circuit is established from the local battery LB, through transmitter d, primary of the transformer T, contact c², fork f, contact c³, switch S, and arm 199, thence to the battery LB. 85

Should another subscriber desire to call up the subscriber who is already engaged, the relative contact rod in that connecting-up apparatus, through which the connection must be made, cannot be actuated. This second caller sets his call apparatus on the desired number. The relative exchange apparatus seeks out another connecting-up apparatus in which the contact devices B, C, 95 D, and E, rotate similarly to the contact devices in the first connecting-up apparatus. But thereby another circuit 182 (or 183) is closed the current in which originating in circuit 183 (shown in dot and dash lines 100 in Fig. 28) from the battery 157 flows from the second connecting-up apparatus through the electro-magnet 179, contacts 106, 85 and 112 in the contact device A, contacts 142, 143 and 141 in the contact device D, contacts 129, 130 and 128 in the contact device E, and afterward flows over through the instrumentality of the connection described between all the contacts of the inner rings in the contact devices E and C of all the 105 connecting-up apparatuses from the contact device C of this second connecting-up apparatus into the relative contact 129, 130 and 128 of the contact device E of the first (engaged) connecting-up apparatus, where 110 the current (now as circuit 183, indicated in full line) flows through the contacts 141, 143 and 142 in the contact device D, contacts 112, 85 and 106 in the contact device A, contacts 148, 149 and 147 in the contact device B, contacts 134, 135 and 133 (or 137) 115 of the contact device C, to make the connection between the contact devices C of all the connecting-up apparatuses back into the second connecting-up apparatus, where 120 125 130

it again flows in circuit 181 (indicated by dot and dash lines) through the contact device C (133 or 137, 135 and 134), contacts 147, 149 and 148 of the contact device B, contacts 116 and 115, and into the battery 157. By the action of this current, the armature of the electro-magnet 179 is drawn back, whereby the connection of the circuit 177 with the electro-magnet 104 in the second connecting-up apparatus is broken so that the relative contact rod bearing the contacts 2400-2499 does not move and the connection with the subscriber called up is not made, whereby also it is rendered impossible for another subscriber to overhear the conversation between the two subscribers who are connected up. When, after the conversation is finished, the calling-up subscriber hangs up his receiver, the lever 34 takes up its original position whereby the arm 3 is set free and moves through its second half-circle.

On the contact 5 engaging the contact 15^a, the connection with the circuit 159 is re-established and the contact device A is thereupon rotated one tooth more, the seventh (167 Fig. 23). Hereby the connection with the electro-magnet 90 is made through the contact 94, 85 and 99. On the contact 4 passing over contact 15, circuit 173 is closed, and the contact device B is thereupon rotated as many teeth as there are uncovered contacts remaining in the group 15 (in this case eight teeth), whereby this contact device is brought back to its zero position. After each further actuation of the contact device A by one tooth, that is the eighth (168, contact 95) the ninth (169, 96) and the tenth (170, 97) the other contact devices are rotated one after the other, C six teeth, D five teeth, and E two teeth, and thus are brought into their zero positions. In Fig. 23 these zero positions are indicated by dot and dash lines.

When the arm 3 in its further movement comes to a stand over the first of the contacts 19, the contact device A is rotated by the eleventh tooth (171), whereby connection is made with circuit 184, the current in which circulates from the battery 157 through the electro-magnet 105, contacts 155 and 154, and contact 103 in the contact device A. Thereby the hook 153 is raised out of the tooth of the contact rod and the latter is returned to its normal position by the spring 185. On the further movement of the arm 3 over the second of the contacts 19, the contact device A is rotated another tooth, the twelfth (172). Hereby the circuit 185 is closed, the current in which circulates from the battery through the electro-magnet 81, contacts 101, 85, and 110, and contacts 116 by the electro-magnet 113, whereby the electro-magnet 81 attracts the lever 73 and the levers 71 and 72 return to

their original position. At the same time the circuit 186 is closed by the contacts 77, 80, coming together, the current in which circuit circulates from the battery through the contacts 59, 67 by the lever mechanism of the exchange call-apparatus, the electro-magnet 70, contacts 49 and 46 on said apparatus, and contacts 77, 80 by the lever mechanism of the connecting-up apparatus. Hereby the lever 69 is displaced, setting free the levers 61 and 54, which return to their original positions. On the arm 3 arriving at the contact 20, the subscriber's call apparatus is brought to a standstill by the stop 31. In this way all the apparatuses are brought back into their original positions.

All the contacts 48, 49, 50, etc., of the first exchange apparatus are connected up with the like contacts 48, 49, etc., on the second and on all the others in order, so that the currents sent from the call-apparatuses of all the other subscribers flow through the said connection to the (first) exchange call apparatus, which has the described connection with all the connecting-up apparatuses, and from here to the disengaged connecting-up apparatuses, which in like manner are sought out by means of the relative exchange apparatus.

Adjacent to the lever 54 by each exchange apparatus, is a knee-shaped lever 187 which is actuated by the current in the electro-magnet 188. This is provided in case the contacts 46 of two or more exchange call apparatuses should simultaneously or almost simultaneously come to a standstill over the contacts 48 which, as already explained correspond to one and the same connecting-up apparatus. In this case the circuit 189 or 190 (Fig. 28) will be closed, the current in which flows through the electro-magnet 188 by the exchange apparatus referred to, so that only that lever 54, the electro-magnet 53 of which is first energized is actuated. The lever 187 of this apparatus is thereupon pressed against the lever 54, while the other levers 54, the electro-magnet of which may have been energized an instant later are prevented from moving owing to this actuation of the lever 187.

Having now fully described my said invention what I claim and desire to secure by Letters Patent is:—

1. An automatic telephone system comprising subscriber's call mechanism, individual selective apparatus and a plurality of line connecting-up apparatus at the exchange, the individual selective apparatus being adapted to select automatically an idle or disengaged line connecting-up apparatus under control of the call mechanism, the latter acting automatically when set for the called number and released to thus control uninterruptedly the said selection and also the operation of the line connecting-up ap-

paratus, contact and lever mechanism one each for the individual and connecting-up apparatus, and a test and control circuit governed thereby so that it is normally closed at one point by the latter, closed at a second point by the former on initiating a call and opened by both on selections made.

2. In an automatic telephone system, exchange apparatus comprising individual selective apparatus and a plurality of line connecting-up apparatus, the latter having numeral selecting devices and a control device therefor, in combination with a subscriber's call-mechanism having a rotatable arm carrying contacts, and fixed contacts co-operating therewith and arranged in groups, one group controlling actuation of the individual apparatus to cause selection of an idle connecting-up apparatus, certain other groups being in pairs the first of a pair controlling the actuation of a numeral selecting device, and the second the return to normal of said device, with adjustable shields for covering a portion of the first and exposing a like portion of the second of such paired groups, and an auxiliary contact for each group controlling the said control device.

3. In an automatic telephone system, subscriber's call-mechanism and exchange mechanism, comprising individual selective apparatus and a plurality of line connecting-up apparatus, the individual apparatus under subscriber's control being adapted to select an idle connecting-up apparatus, the latter comprising slidable contact rods whereon appear the terminals of subscriber's lines grouped numerically by the respective rods, fixed terminals for co-operating therewith and likewise arranged, like fixed terminals of the respective groups being joined, contact devices for selecting the desired terminal comprising fixed contacts and rotatable disks under subscriber's control, one such device controlling the others, certain of said others having their fixed contacts connected to said joined terminals, and certain others controlling the selection and actuation of a rod, and electro-magnetic actuating means for the contact device and rods.

50 4. In an automatic telephone system, subscriber's call-mechanism and exchange mechanism, comprising individual selective apparatus and a plurality of line connecting-

up apparatus, the individual apparatus under subscriber's control being adapted to select an idle connecting-up apparatus, the latter comprising slidable contact rods whereon appear the terminals of subscriber's lines grouped numerically by the respective rods, fixed terminals for co-operating therewith and likewise arranged, like fixed terminals of the respective groups being joined, contact devices for selecting the desired terminal comprising fixed contacts and rotatable disks under subscriber's control, one such device controlling the others, certain of said others having their fixed contacts connected to said joined terminals, and certain others controlling the selection and actuation of a rod, and electro-magnetic actuating means for the contact device and rods, together with means for preventing the actuation of a selected rod if the subscriber's line selected be busy in another connection.

5. In an automatic telephone system, subscriber's call-mechanism and exchange mechanism, comprising individual selective apparatus and a plurality of line connecting-up apparatus, the individual apparatus under subscriber's control being adapted to select an idle connecting-up apparatus, the latter comprising slidable contact rods whereon appear the terminals of subscriber's lines grouped numerically by the respective rods, fixed terminals for co-operating therewith and likewise arranged, like fixed terminals of the respective groups being joined, contact devices for selecting the desired terminal comprising fixed contacts and rotatable disks under subscriber's control, one such device controlling the others, certain of said others having their fixed contacts connected to said joined terminals, and certain others controlling the selection and actuation of a rod, and electro-magnetic actuating means for the contact device and rods, together with means whereby when the subscriber restores his receiver, the call-mechanism is enabled to cause the exchange devices brought into use to be returned to normal condition.

In testimony whereof I have hereunto set my hand in presence of two witnesses.
